MODEL STOP-GO TRAFFIC LIGHT

Robert E. Davis, Jr., Wallingford, Conn., assignor to
The A. C. Gilbert Company, New Haven, Conn., a
corporation of Maryland

Filed June 18, 1962, Ser. No. 203,073
12 Claims. (Cl. 340—84)

This invention relates to an operative replica in miniature size of stop-go traffic lights as commonly used at road or street intersections. Such devices comprise a box suspended over or supported on a post at road intersections containing at least red and green light projecting windows in side walls of the box that face in predetermined directions aligned respectively with two or more roads or streets that meet at the intersection.

An object of the invention is to solve problems arising from the scarcity of space for a source of illumination in a very miniature structure by reducing the number and size of electric lamps required to illuminate in segregated groups as many as four light projecting windows at one time so as to display a red light in one or both directions to traffic approaching the intersection along one street and simultaneously display a green light in one or both directions to traffic approaching the intersection on an intersecting or cross street.

Another object is to change the colors of light so directed toward each of such streets from red to green and vice versa by the alternate lighting and extinguishment of only two electric lamps, either of which will be lighted when the other lamp is extinguished. The present improvements accomplish this by merely shifting current from the circuit of one lamp to the circuit of the other lamp thus requiring for remote control only a simple, double-throw, electric switch. This eliminates the need of moving parts or electrical components in addition to the lamps themselves within the signal box.

A related object is to make a miniature signal box of easily separated molded plastic parts which can be snapped together and taken apart by simple finger manipulation without the use of tools when lamp bulbs need servicing or replacement.

These and other objects of the invention will appear in fuller detail in connection with the following description of a simple embodiment of the invention having reference to the accompanying drawings wherein:

FIG. 1 is a plan view of the signal box showing its top wall partially broken away to expose the contours of the interior construction.

FIG. 2 is a view taken in section on the plane 2—2 in FIG. 1 looking in the direction of the arrows.

FIG. 3 is a view taken in section on the plane 3—3 in each of FIGS. 1 and 2 looking in the direction of the arrows.

FIG. 4 is an isometric view of one section of the signal box.

FIG. 5 is a similar view of the companion section of the signal box.

FIG. 6 is a diagram showing the projections of colored light from the box when one of the lamps is lighted and the other lamp extinguished.

FIG. 7 is a corresponding diagram of changed projection of colored light from the box when the said other lamp is lighted and the first mentioned lamp is extinguished.

Referring to FIGS. 4 and 5 the signal box 12 is shown to comprise a casing having two U-shaped sections 13 and 14, one of which sections provides the top wall 15 of the box and the other of which sections provides the bottom wall 16 of the box. The box section 14 has lugs 17 projecting inward from its side walls at a short distance above the bottom wall 16 and the box section 13 has four

corresponding lugs 18 which interlock with lugs 17 when the two sections are placed together. This is possible because of the resilience of the plastic material of which box section 13 is made which enables the side walls to spring apart sufficiently to permit the ends of lugs 18 to pass the ends of lugs 17 and then snap into interlocking relation therewith so as to occupy the space between lugs 17 and the bottom wall of section 14.

Section 14 has its space between its side walls spanned by a light baffling partition 20 that extends from the top wall 15 to the bottom wall 16 of the box in a zig-zag course thus separating the box interior into a sealed light chamber 21 shown at the left of FIG. 2 and a separate sealed light chamber 22 shown at the right of FIG. 2. These two chambers are isolated from each other by the partition 20 in a manner to prevent transfer of light therebetween. Each chamber extends from the top wall 15 to the bottom wall 16 of the box. The partition 20 between the chambers is contoured to form a nipple-like light transmitting conduit 23 leading from chamber 22 to the box window 24 and to form a like nipple or conduit 25 extending across chamber 22 to the box window 26. All of the other box windows 32 to 37, inclusive, are located in the relationship shown in the drawings. Windows 32, 36 and 37 give out light only from chamber 22, while windows 33, 34 and 35 give out light only from chamber 21.

The source of illumination inside of signal box 12 as illustrated herein comprises two miniature electric lamp bulbs 42 and 43, the former of which illuminates chamber 22 and transmits light through nipple 23 to window 24. All light from lamp 42 is excluded from chamber 21 because the end of nipple 23 abuts against a light filtering pane 44 of red transparent plastic whose margin is nested in a counterbore of window 24. In like manner light from the other lamp 43 is excluded from chamber 22 because the ends of nipple 25 abut against a light filtering pane of green transparent plastic 45 whose margin is nested in a counterbore of window 26. Each lamp need consist only of an exhausted miniature glass bulb containing the filament and in which are embedded the two insulated wires 53, 54 or 55, 56 that conduct current to the lamp.

FIG. 8 shows that current can be supplied to either lamp alone, and simultaneously cut off from the other lamp, by merely throwing the remote control electric switch 52 from full line to broken line position which will shift current from a supply line 57 to the desired lamp for proper traffic control.

Each of the eight windows is covered respectively by light filters like 44 and 45 whose colors are indicated by vertical lines for the color red and diagonal lines for the color green. It will thus be seen from the drawing that when lamp 42 alone is in circuit, light will be projected as indicated by the arrows in FIG. 6 from only the two red windows 24 and 32 in the upper level of the box and simultaneously from the two green windows 36 and 37 in the lower level. However when switch 52 is thrown to reverse position the signal lighting will be changed so that light is projected as shown in FIG. 7 from only the two red windows 34 and 35 in the upper level of the box and simultaneously from the two green windows 26 and 33 in the lower level. The lighting condition in FIG. 6 signals traffic to move in both directions on the east-west oriented street or road and to stop in both directions on the north-south oriented cross street or road. In FIG. 7 the lighting condition has been changed to permit traffic flow in both directions on the north-south oriented street and to signal traffic to stop on the east-west oriented street or road. Arrows indicating projected lights and also points of the compass are designated as usual "N" for North, "S" for South, "W" for

West and "E" for East. In FIGS. 6 and 7 those windows which are projecting no light are darkened by stippling.

The open notch in the free end of the forked brackets 53 and 59 may be of size and shape to enable the twisted and individually insulated stiff electric wires 53, 54 or 55, 56 to wedge firmly but removably therein whereby to hold the lamp bulbs 42 and 43 steadily in line with the light transmitting nipples 23 and 25. The internal surfaces of the box that enclose the chambers 21 and 22 are preferably colored brilliant white or silver to make all surfaces bounding the chambers a source of reflected light. This will occur even more effectively because of the extremely small size of the signal box whose outside dimensions to accord with model traffic systems need not be greater than 1 1/4" high by 3/4" square in cross section. The importance of these improved features of construction in making an operative traffic signal light in such tiny size will be evident.

The signal box may be supported in any appropriate manner as by holding engagement of the recessed opening in the top wall 15 with the open end of a downward directed supporting conduit (not shown) through which may be threaded the insulated electric wires 53, 54, 55 and 56. Such conduit will seal the top opening against escape of light.

With reference to the wording of certain of the following claims it will be understood that in the illustrative embodiment of the invention now described, three windows 32, 34 and 35 are in the same chamber 22 in the upper portion of the box and constitute three windows of a group of four windows 24, 32, 34 and 35 which three windows are on an opposite side of partition 20 from the fourth window 24, and in like manner three windows, 33, 36 and 37 are in a common chamber 21 in the lower portion of the box and constitute three windows of a group of four windows 26, 33, 36 and 37 which three windows are on an opposite side of partition 20 from the fourth window 26.

Many departures from this precise number and arrangement of windows in relation to the box sides and to the partition 20 can evidently be made within the principles of these improvements and all such that come within the definitions of the claims are intended to be within the coverage of the solicited patent.

What is claimed is:

1. A model stop-go changeable traffic light comprising a box having opaque side walls and an opaque partition extending upward and downward between two of said side walls in a manner to divide the interior of said box into two laterally adjacent chambers isolated by said partition against transmission of light therebetween, each of said chambers including and occupying both an upper portion and a lower portion of the interior of said box, a separate electric lamp bulb in each of said chambers, at least two windows in side walls of said box which face in respectively different directions each of said windows opening outward from a different one of said chambers, and means alternately to light said lamp bulbs only one at a time.

2. A model stop-go changeable traffic light as defined in claim 1, in which one of the said windows is in the said upper portion of the said box, and the other of said windows is in the said lower portion of said box and both of said windows are lighted by the same lamp bulb.

3. A model stop-go changeable traffic light as defined in claim 1, in which one of the said windows is spanned by a red color filter and the other of said windows is spanned by a green color filter.

4. A model stop-go changeable traffic light as defined in claim 2, in which one of the said windows is spanned by a red color filter and the other of said windows is spanned by a green color filter.

5. A model stop-go changeable traffic light comprising a box having first and second pairs of side walls, the walls of said pairs being spaced apart and facing in four

different directions respectively, a partition extending from a first side wall to a second side wall of said first pair in a manner to divide the interior of said box vertically into two chambers isolated by said partition against transmission of light therebetween, each of said chambers occupying both an upper portion and a lower portion of said box, a separate electric lamp bulb in each of said chambers, a light projecting window in each of said side walls of said first pair at one side of said partition in said upper portion of said box, and a light projecting window in each of said side walls of said second pair on the other side of said partition in said lower portion of said box, whereby light from either of said lamps alone can be projected from said box simultaneously through windows in the side walls of said first pair in the lower portion of said box and through windows in the side walls of said second pair in the upper portion of said box and simultaneously baffled by said partition from reaching windows in other than side walls of said first and second pairs, and remote electrical control means operative to light said lamp bulbs alternately and only one at a time.

6. A model stop-go changeable traffic light comprising a box having opaque side walls and an opaque partition extending upward and downward between two of said side walls in a manner to divide the interior of said box into two laterally adjacent chambers isolated by said partition against transmission of light therebetween, each of said chambers including and occupying both an upper portion and a lower portion of the interior of said box, a separate electric lamp bulb in each of said chambers, at least two windows in side walls of said box which face in respectively different directions each of said windows opening outward from a different one of said chambers, means alternately to light said lamp bulbs only one at a time, two additional side walls bounding the said two chambers respectively one on each side of the said partition and containing the said windows respectively, together with a light transmitting conduit having light confining walls and an open end terminating at a first one of said windows, said conduit extending across a first one of said chambers and opening through said partition into the other of said chambers, whereby light from said other chamber is transmitted to said first window through said conduit while isolated from said first chamber.

7. A model stop-go changeable traffic light as defined in claim 6, in which the said opaque partition has a diagonally extending portion offsetting its upper end laterally in relation to its bottom end.

8. A model stop-go changeable traffic light as defined in claim 6, together with red color filters spanning all of the said windows in one of the said upper and lower portions of the said box, and filters of a different color spanning all of the said windows in the other of said portions of said box.

9. A model stop-go changeable traffic light as defined in claim 6, in which there is a group of four light projecting windows in four of the said side walls respectively all located in said upper portion of said box, and another group of at least four light projecting windows in four of said side walls respectively all located in said lower portion of said box, three of said windows in each of said groups of four windows being on a common side of the said partition opposite the other said common side.

10. A model stop-go changeable traffic light as defined in claim 9, in which the fourth window in each of the said groups of light projecting windows is on a different side of the said partition from the said three windows of said group, together with a light transmitting conduit leading through said partition to each of said fourth windows from the said chamber on the opposite side of said partition therefrom.

11. A model stop-go changeable traffic light as defined in claim 9, in which all windows in the said upper portion of the said box are spanned by red color light filters

to signal "stop" when illuminated, and all windows in the said lower portion of said box are spanned by green color light filters to signal "go" when illuminated.

12. A model stop-go changeable signal light as defined in claim 9, in which the said box comprises two U-shaped sections separably assembled, each of said sections carry-

ing two of the said side walls and four of the said windows.
